UNITED STATES PATENT OFFICE.

JOHN W. BRANDON, OF ST. LOUIS, MISSOURI, ASSIGNOR OF ONE-HALF TO
EDWARD WEHRHAN, OF SAME PLACE.

DESIGN FOR A BRUSH.

SPECIFICATION forming part of Design No. 34,171, dated March 5, 1901.

Application filed January 21, 1901. Serial No. 44,225. Term of patent 14 years.

To all whom it may concern:

Be it known that I, JOHN W. BRANDON, of the city of St. Louis, State of Missouri, have invented and produced a new and original 5 Design for a Brush, of which the following is a full, clear, and exact description, reference being had to the accompanying drawings, forming a part hereof.

Figure 1 is a side elevation of my complete 10 design. Fig. 2 is a longitudinal sectional view of the same.

The material or essential features of my design consist of an acorn-shaped enlargement on the inner end of the brush - handle, the 15 outer end 1 of which is larger than the inner end 2, the said acorn-shaped enlargement 3 being of greater diameter than is the part 1

of the handle. A ferrule 4 surrounds the inner end of the enlargement 3, and the outer end 5 of the said ferrule is of smaller diameter 20 than its inner end and incloses the brush-bristles 6. The said ferrule appears as the acorn-nut, while the visible portion of the enlargement 3 appears to be the cupule.

I claim—

The design for a brush, substantially as herein shown and described.

In testimony whereof I affix my signature in presence of two witnesses.

JOHN W. BRANDON.

Witnesses:

EDWARD E. LONGAN,
ALFRED A. EICKS.
